[57] **CLAIM**

The ornamental design for a outer surface of a power supply bezel, as shown and described.

DESCRIPTION

FIG. 1 is a perspective view of the outer surface of a power supply bezel showing our new design. The broken line showing throughout the drawings is included for the purpose of illustrating environmental elements only and forms no part of the claimed design;

FIG. 2 is a top plan view thereof;

FIG. 3 is a front elevational view thereof;

FIG. 4 is a left side elevational view thereof;

FIG. 5 is a right side elevational view thereof;

FIG. 6 is a bottom plan view thereof;

FIG. 7 is a perspective view of a second embodiment of a outer surface of a power supply bezel showing our new design;

FIG. 8 is a top plan view thereof;

FIG. 9 is a front elevational view thereof;

FIG. 10 is a left side elevational view thereof;

FIG. 11 is a right side elevational view thereof; and,

FIG. 12 is a bottom plan view thereof.

FIG. 1.

FIG. 2.

FIG. 3.

FIG. 4.

FIG. 5.

FIG. 6.

FIG. 7.

FIG. 8.

FIG. 10.

FIG. 9.

FIG. 11.

FIG. 12.
